UNITED STATES PATENT OFFICE.

HAROLD G. ESSAYAN, OF BROOKLINE, MASSACHUSETTS.

DESIGN FOR A RING.

55,558.

Specification for Design.

Patented June 29, 1920.

Application filed December 5, 1919. Serial No. 342,850. Term of patent 3½ years.

To all whom it may concern:

Be it known that I, HAROLD G. ESSAYAN, a citizen of the United States, residing at Brookline, in the county of Norfolk and Commonwealth of Massachusetts, have invented a new, original, and ornamental Design for a Ring, of which the following is a specification, reference being had to the accompanying drawing, forming a part hereof in which—

The figure is a perspective view of a ring showing my new design.

I claim the ornamental design for a ring as shown.

HAROLD G. ESSAYAN.
